(57) CLAIM

The ornamental design for a tennis racquet, as shown and described.

DESCRIPTION

FIG. 1 is a front perspective view of an embodiment of a tennis racquet showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the tennis racquet that forms no part of the claimed design. The heavier and lighter stippling is shown to illustrate a contrasting appearance.
